GLOVE

Julius A. Higier, Johnstown, N. Y.

Application November 27, 1956, Serial No. 43,967

Term of patent 3½ years

(Cl. D3—11)

The bows showing in Figure 1 are superimposed on the back of the glove by means of embroidery.

I claim:

The ornamental design for a glove, substantially as shown and described.
